(57) CLAIM

The ornamental design for a medical patch, as shown and described.

DESCRIPTION

1. Medical patch

The broken lines shown in Figure 1.3 illustrate portions of the medical patch that form no part of the claimed design.
